SEWING MACHINE RUFFLER

Filed July 15, 1929

Inventor:

Andrew J. Karmichael,
by Calvert Talbot,
1869.

UNITED STATES PATENT OFFICE

ANDREW J. CARMICHAEL, OF NEW HAVEN, CONNECTICUT, ASSIGNOR TO THE GREIST MANUFACTURING COMPANY, A CORPORATION OF CONNECTICUT

SEWING MACHINE RUFFLER

Application filed July 15, 1929. Serial No. 378,480.

This invention relates to an improvement in the ruffler shown in the Greist and Boyler Patent No. 1,044,645, dated November 19, 1912, and has for its object to provide a construction having certain advantages over the construction shown in the said patent, as will be hereinafter fully set forth. In the construction shown by the patent just referred to, when the adjustable ratchet wheel 10 is lifted for five-stitch ruffling the action of the operating pawl for said ratchet wheel was in such a direction that there was a tendency to push the said ratchet wheel downward into position for single stitch ruffling, and it was therefore necessary to provide positive locking means for holding the plate or lever on which the ratchet wheel was mounted in five-stitch ruffling position, and this locking means is not required in the present improved construction, owing to the manner of mounting the adjustable plate which carries the ratchet-wheel or wheels.

In the accompanying drawings Figs. 1 and 2 are opposite side views of the improved ruffler. Fig. 3 is a view similar to Fig. 2 but showing certain parts in different positions. Fig. 4 is an end view looking from the left of Figs. 2 and 3. Fig. 5 is an enlarged detail view of some parts shown in Figs. 2 and 3. Referring to the drawing, 12 denotes a standard which is a part of the frame of the ruffler, and which frame is preferably provided with an integral attaching portion or shank 13 by which the attachment may be secured to the presser-bar of a sewing machine in substitution of an ordinary presser-foot, the attachment including, as is usual, a presser-foot portion 14. Pivotaly mounted on a pin or rivet 15, passing through the upper part of the standard 12, is an operating lever 16 which is forked at its forward or free end for engagement with a roller-stud or pin to be carried by the needle-bar of a sewing machine; and also mounted on the said stud or rivet 15 is a pendulous lever 17 to the lower end of which is jointed a carrier 18 for the ruffling blade 19.

The operating lever 16 carries a spring pressed pawl-carrier 20 having, integral therewith, a pawl 20^a which is arranged to

engage a shoulder 21 on the pendulous lever 17, when, in the upward movement of the operating lever 16, the ruffling blade is to be thrown forward for the ruffling stroke.

Also mounted on the operating lever 16 is an adjustable contact screw 22 the lower end of which is arranged to engage the upper end of a contact finger 23 on the pendulous lever 17, for the purpose of moving the said lever backward to retract the ruffling blade. The throw of the ruffling blade may be regulated by adjustment of the said screw 22 which provides for more or less lost motion between the operating lever and the pendulous lever.

Pivottally attached to the standard or frame portion 12 of the ruffler is a plate or lever 24 pivoted on a pin or rivet 24^a. Mounted on said plate or lever 24 is a ratchet wheel 26 having two deep notches 27 and a series of five shallow notches 28 between said deep notches. The fulcrum or pivotal point 24^a of said plate or lever 24 is eccentric to the pin or rivet 25 on which the said ratchet wheel is mounted, so that by adjusting the said plate or lever 24 on its fulcrum point the said ratchet wheel may be depressed to the lowered position shown in Fig. 3, or lifted to the raised position shown in Fig. 2. When the plate or lever 24 is in the position shown in Fig. 3, the ratchet wheel 26, mounted on said plate or lever, will be below the path of movement of the pawl 20^a, so that said pawl may engage the shoulder 21 on the pendulous lever 17 at each upward stroke of the operating lever 16, thereby imparting a forward movement to the ruffling blade at each stitch of the sewing machine. When, however, the ratchet wheel is in the raised position shown in Fig. 2 the spring-pressed pawl 20^a, in engaging the shallow notches in said ratchet wheel, will be held above the said shoulder 21 until, in the rotation of the ratchet wheel, a deep notch 27 comes beneath said pawl, and the latter will then fall low enough to engage the shoulder 21 and will therefore impart a forward or ruffling stroke to the said ruffling blade.

The operation of the parts thus far described is essentially the same as in the ruffler of the said Patent No. 1,044,645. In the

present improved construction, however, the plate or lever 24 is pivoted to the frame standard 12 at a point below and beyond the pin or rivet 15 on which the operating lever, carrying the spring-pressed pawl which actuates the ratchet wheel, is mounted; so that when said ratchet wheel is lifted to its raised position, for five-stitch ruffling, the pressure of the said pawl on said ratchet wheel will not have a tendency to push the said wheel downward, to single stitch position, as in the construction shown in the said Patent No. 1,044,645, the pressure of said pawl on said ratchet wheel, in this improved construction, having a tendency to hold the ratchet wheel up in five-stitch ruffling position, rather than otherwise. In other words, as the pivotal point 24^a of the ratchet-wheel carrying-plate 24 is beyond or rearward of the pivotal point 15 of the operating lever 16 on which the pawl carrier 20 is mounted, the action of the pawl 20^a on said ratchet-wheel serves to hold or lock said plate 24 in place when said wheel is in position to be engaged by said pawl. The plate or lever 24 is provided with a slot 29 through which passes a pin or rivet 30 fixed to the frame standard part 12, and beneath the head of said rivet is a spring washer 31 which holds the said plate or lever in either of the positions to which it may be adjusted. In adjusting the plate or lever 24 to either of the positions referred to, the walls at the ends of said slot 29 will engage the said rivet 30 and thus determine and limit the adjusting movements of said plate or lever.

Fixed to the said plate or lever 24 is a spring 32 having a lug 33 held in yielding contact with the ratchet wheel 26 and engaging the notches in said ratchet wheel in such a manner that said spring serves as a detent pawl to prevent backward movement of said ratchet wheel.

It will therefore be understood that in the operation of the improved construction herein described the locking means shown in Patent No. 1,044,645, hereinbefore referred to, is omitted without detriment to the operation of the ruffler, as, in this improved construction, the ratchet wheel cannot be pushed downward from its raised position to its lowered position by the pressure of the pawl 20^a. The plate or lever 24 is provided with a finger piece 24^b by which the adjustment of said plate or lever may be conveniently effected.

While the ratchet wheel herein shown is constructed with two deep notches and five shallow notches between said deep notches, for six-stitch ruffling, the said ratchet wheel may be constructed with any desired number of deep or shallow notches without departing from the scope of the present invention.

From the foregoing it will be understood that single-stitch or six-stitch ruffling may

be performed by the improved ruffler herein shown, and when plain sewing is to be done the ruffler may be thrown out of operation simply by adjusting the pawl-carrier 20 to the position shown in Fig. 3, in which inoperative position the said pawl-carrier will be held by a finger 36 on a spring 37 attached to the operating lever 16. Also, instead of a single ratchet wheel, as herein shown, two ratchet wheels having deep and shallow notches, and one of which wheels is adjustable relative to the other may be employed if desired.

Having thus described my invention I claim and desire to secure by Letters Patent:

1. In a sewing machine ruffler, the combination with a suitable frame, of a ruffling blade, an operating lever pivoted to said frame and operatively connected to said blade, a pawl-carrier mounted on said lever and provided with a pawl, a ratchet-wheel to be engaged at times by said pawl and having deep and shallow notches, and a plate by which said ratchet-wheel is carried and which plate is adjustably mounted on said frame by a pivot located eccentric to said ratchet-wheel and below and rearward of the pivotal point of said operating lever; whereby, when said ratchet-wheel is in raised position to be engaged by said pawl the latter will act to hold or lock said plate in its adjusted position.

2. In a sewing machine ruffler, the combination with a suitable frame, of a ruffling blade, an operating lever pivoted to said frame and operatively connected to said blade, a pawl-carrier mounted on said lever and provided with a pawl, a ratchet-wheel to be engaged at times by said pawl and having deep and shallow notches, and a plate by which said ratchet-wheel is carried and which plate is adjustably mounted on said frame by a pivot located eccentric to said ratchet wheel and below and rearward of the pivotal point of said operating lever; whereby, when said ratchet-wheel is in raised position to be engaged by said pawl the latter will act to hold or lock said plate in its adjusted position, said adjustable plate having a slot, and a pin or rivet fixed to said frame and entering said slot the end walls of which, co-operating with said pin or rivet, serve to limit the adjusting movements of said plate.

In testimony whereof I affix my signature.

ANDREW J. CARMICHAEL.
